UNITED STATES PATENT OFFICE.

ARTHUR BENT AND JOHN HERBERT WHITELEY, OF STOCKPORT, ENGLAND.

RING AND FLIER DOUBLING-FRAME.

965,065.

Specification of Letters Patent. Patented July 19, 1910.

Application filed November 18, 1909. Serial No. 528,714.

To all whom it may concern:

Be it known that we, ARTHUR BENT and JOHN HERBERT WHITELEY, subjects of Great Britain, residing at Stockport, in the county 5 of Chester, England, Kingdom of Great Britain, have invented new and useful Improvements in and Connected with Ring and Flier Doubling-Frames, of which the following is a specification.

10 Our invention relates to improvements in and connected with ring and flier doubling frames and has for its object the construction of an improved fourfold and roller lap preventer which can be readily attached to 15 any type of frame, and is simple and reliable in action.

Our improved four-fold and roller lap preventer is as usually controlled by an arm resting upon the thread and consists chiefly 20 of a trap comprising a fixed surface and a screw-threaded spindle employed at the back of the roller in the path of the thread and having a tumbling weight and an arm fulcrumed to the latter, a portion of which 25 arm normally rests upon the thread and when the thread breaks falls upon the bottom roller and being moved back thereby causes the tumbling weight to fall and turn the said screw-threaded spindle and the latter to press its end against the said surface, 30 and thereby nip the thread at the back of the roller.

We attain this object by the mechanism illustrated in the accompanying drawing, in 35 which—

Figure 1 is a front view. Figs. 2, 3 and 4 are sectional end views of a portion of a ring doubling frame provided with our improved four-fold and roller lap preventer. 40 Figs. 5 and 6 are respectively a sectional front view and an end view of the said preventer enlarged.

Similar letters refer to similar parts throughout the several views.

45 In carrying out our invention and referring to Figs. 1, 2, 3 and 4, *a* is the bottom and *b* the top roller, *c* the roller cap-bar, *d*, *e*, *g* the said trap, *h* the tumbling weight, and *i*, *k*, *l* the arm fulcrumed thereto. The 50 said trap is carried by a bracket *m* which may be hooked or secured to the top roller cap-bar *c* (or any other suitable part of the frame) and may be in the form of a boss *d*, see more particularly Figs. 5 and 6, which 55 has a cut *e* half way across for the thread *n* to pass through and longitudinally a screw-

threaded hole *f* extending from one end of the boss *d* through to the cut *e* and containing a screw-threaded spindle *g* to the outer end of which is secured the tumbling weight *h*, the side of the said cut opposite to the free or inner end of the said spindle forming a nipping surface for the thread *n* against which the said free or inner end operates. In the present instance the said weight arm 60 is made in three parts, the part *i* having a spiral eye *o* and being adjustably secured to the part *k* and the latter pivoted to the part *l*. The part *l* has a rearwardly extending projection *p* adapted to normally bear 70 underneath the cap-bar *c*, see Figs. 2 and 3, and thereby take the pressure of the tumbling weight *h* and arm part *l* off the thread *n*.

If desirable the part of the boss *d* against 75 which the screw-threaded spindle *g* operates may contain a screw *g*, as shown in Fig. 5, the inner end of which forms the said nipping surface so that the latter can be adjusted in relation to the free or inner end of the 80 spindle *g* and thereby wear may be compensated for.

The four-fold and roller lap preventer described operates as follows: While the thread *n* is intact, the relative position of the parts 85 composing the said preventer is such as shown in Figs. 1 and 2, namely the front end of the part *i* of the arm *i*, *k*, *l* rests upon the thread *n*, the screw-threaded spindle *g* is slightly withdrawn and allows the thread to 90 freely pass through the cut *e*, the tumbling weight *h* is approximately in an upright position and the projection *p* of the arm-part *l* bears underneath the roller cap-bar *c*. When the thread breaks, the arm parts *i* 95 and *k* drop, the latter upon the bottom roller *a* as shown in Fig. 3, and being thus in frictional contact with the roller *a* it is moved back thereby, which causes the other part of the arm to push the tumbling weight *h* over 100 its center and thus turn the screwed spindle *g* inward and nips the thread in the cut *e*, as shown in Fig. 4. After the thread has been pieced, the arm *i*, *k*, *l* and tumbling weight *h* are brought back into their normal 105 position as shown in Figs. 1 and 2.

We claim:

1. In a ring and flier doubling frame, a stationary surface in the path of the thread at the back of the rollers, a screw-threaded 110 spindle opposite to the said surface and means under the control of the thread for

turning the said spindle and thereby press the thread against the said surface and nip the thread when it breaks, all combined substantially as and for the purpose set forth.

5 2. In a ring and flier doubling frame, a bracket at the back of the rollers having a boss and a cut across the said boss forming a stationary surface, a screw-threaded spindle in the said bracket opposite to the said 10 surface and means under the control of the thread for turning the said spindle and thereby press the thread against the said surface and nip the thread when it breaks, all combined substantially as and for the purpose set forth.

15 3. In a ring and flier doubling frame, a stationary surface in the path of the thread at the back of the rollers, a screw-threaded spindle opposite thereto, a tumbling weight secured to the said screw-threaded spindle 20 and an arm fulcrumed to the said weight projecting over the bottom roller forward and supported by the thread when intact,

all combined substantially as and for the purpose set forth.

25

4. In a ring and flier doubling frame, a stationary surface in the path of the thread at the back of the rollers, a screw-threaded spindle opposite thereto, a tumbling weight secured to the said screw-threaded spindle, 30 an arm fulcrumed to the said weight projecting over the bottom roller forward and supported by the thread when intact, the said arm being formed in three parts pivotally connected together, the parts fulcrumed 35 to the said weight having a rearwardly extending projection, all combined substantially as and for the purpose set forth.

In testimony whereof we have signed our names to this specification in the presence of 40 two subscribing witnesses.

ARTHUR BENT.

JOHN HERBERT WHITELEY.
